UNITED STATES PATENT OFFICE.

CHARLES WIRT, OF CHICAGO, ILLINOIS.

DESIGN FOR AN INSULATOR-BRACKET.

SPECIFICATION forming part of Design No. 21,454, dated April 12, 1892.

Application filed October 23, 1891. Serial No. 409,625. Term of patent 3½ years.

To all whom it may concern:

Be it known that I, CHARLES WIRT, a citizen of the United States, residing at Chicago, in the county of Cook and State of Illinois, 5 have invented and produced a new and original Design for Brackets for Electric Wires, of which the following is a specification.

My invention relates to improvements in designs which I have produced for electric-wire brackets or brackets for supporting insulators for electric wires. It is illustrated in the accompanying drawings, wherein—

Figure 1 is a side view of a bracket. Fig. 2 is a plan view thereof.

Like parts are indicated by the same letter 15 in both figures.

A is the flat arm of the bracket; B, a cylindrical insulator-support at its outer end; G G, flat curved flanges above and below the arm, and D the flat supporting-plate at one end 20 of the arm.

I claim—

The design for an insulator-bracket, substantially as shown and described.

CHARLES WIRT.
